UNITED STATES PATENT OFFICE

155,879

DESIGN FOR AN OUTDOOR SERVICE RESTAURANT STAND

Juanita J. Elliott, Lathrop, Calif.

Application August 26, 1948, Serial No. 148,306

Term of patent 7 years

(Cl. D13—1)

To all whom it may concern:

Be it known that I, Juanita J. Elliott, a citizen of the United States, residing at Lathrop, in the county of San Joaquin and State of California, have invented a new, original, and ornamental Design for an Outdoor Service Restaurant Stand, of which the following is a specification, reference being had to the accompanying drawing, forming a part thereof.

The figure is a front perspective view of an outdoor service restaurant stand, showing my new design.

The back of the design is substantially plain and the opposite side is similar to the side shown.

I claim:

The ornamental design for an outdoor service restaurant stand, as shown and described.

JUANITA J. ELLIOTT.
